CUMMERBUND

Donald Mayer, West Hempstead, N.Y., assignor to H & M Neckwear Co., Inc., New York, N.Y.

Application September 24, 1958, Serial No. 52,742

Term of patent 14 years

(Cl. D3—10)

Fig. 1 is a front view of a cummerbund showing my design; and also showing the rest of the cummerbund in phantom;

Fig. 2 is a horizontal cross-section taken on the line 2-2 of Fig. 1, the thickness of the fabric being exaggerated.

The essential features of the design reside in the portions shown in solid lines on the drawing and consist of two sets of vertical pleats spaced apart from one another across the front of the cummerbund.

I claim:

The ornamental design for a cummerbund, as shown and described.
